Patented Feb. 16, 1965

200,342

LAMP

Julius I. Dahab, Little Neck, N.Y., assignor to Dabs International Corporation, New York, N.Y., a corporation of New York

Filed Nov. 29, 1963, Ser. No. 77,619

Term of patent 14 years

(Cl. D48—20)

FIG. 1

FIG. 2

FIG. 3

FIG. 4

FIG. 5

The undisclosed rear of the lamp is substantially the same in appearance as the front shown.

I claim:

The ornamental design for a lamp, as shown and described.
